BACKSTOP MECHANISM FOR BOWLING PIN SPOTTING MACHINES

Rupert E. Rundell, Rockville Centre, N. Y., assignor to American Machine and Foundry Company, a corporation of New Jersey

Application October 29, 1946, Serial No. 706,472.

14 Claims. (Cl. 273—43)

1

This invention relates to bowling pin spotting machines and more particularly to improvements in such machines effecting the more efficient handling of bowling pins and bowling balls in order to remove pins and balls from the pit of a bowling alley and make them available for spotting on the alley and return to the player, respectively.

The present invention constitutes a solution of the problems of handling bowling pins as little as possible in effecting their return to pin spotting mechanism, and the return of balls to the player especially where there is a minimum of space available for the movement of the ball relative to the frame of the machine due to close positioning of kickbacks of two adjoining alleys on which a common ball return is provided for the two alleys.

The mechanism constituting the present invention is designed primarily for use with bowling pin setting machines of the types shown in Rundell patent, No. 2,388,707, issued November 13, 1945, for Bowling Pin Setter, and co-pending Broekhuysen application, Serial No. 627,605, filed November 9, 1945, for Bowling Pin Setting Machine, now Patent 2,559,274, granted July 3, 1951. It is to be noted, however, that this mechanism is not to be considered limited to such machines, as it may find use in other types of bowling pin setting machines.

According to the invention, in handling bowling pins which are to be delivered to the spotting mechanism, there is provided a movable backstop which is raised vertically a distance greater than the maximum diameter of the largest ball used, so that after each ball is thrown, deadwood or unwanted standing pins which are swept from the alley and the ball can be moved rearwardly beneath the backstop into the range of action of coacting ball lifting, and pin distributing mechanisms.

The backstop is normally positioned with its lower edge closely adjacent the bottom of the pit of the alley, so that all pins and balls falling or rolling into the pit are prevented from passing beneath the backstop until the latter is raised, whereupon the ball and pins can be moved by conveying mechanism onto the ball lift, and to the pin distributing conveying mechanism, respectively. This makes it impossible for the relatively heavy balls to travel rearwardly past the backstop until the ball lift mechanism is positioned to receive it, and thereby breakage of machine parts is prevented.

The invention also takes into consideration the problem of handling bowling pins a plurality of times before they are forwarded to the conveying

5 mechanism which delivers them to the pin spotter more rapidly than heretofore possible thereby speeding up the game cycle of the machine. This is because as soon as the backstop is raised, all pins in the pit are conveyed directly therebeneath in one general direction only and delivered to the pin distributing conveyor. Consequently, this results in the minimum of pin handling during each pin distributing operation because it eliminates raising, dropping and tumbling the pins being assembled for delivery to the pin distributing mechanism and, therefore, there is less pin breakage and a material lessening of noise and clatter during each pin handling operation after the rolling of each ball of a frame.

10 It is an object of my invention to provide a bowling pin setting machine having improved ball and pin handling mechanisms operating in conjunction with a vertically movable backstop which permits more satisfactory and efficient distribution of pins, and return of the ball to the player with a minimum of lifting of the pins and substantial elimination of alterations and modifications to the sides of the kickbacks.

15 It is a further object of the invention to provide an improved bowling pin setting machine having a backstop which is moved out of the path of travel of balls and pins advancing therebeneath to ball and pin handling and distributing mechanism.

20 It is a further object of the invention to provide mechanism for conveying bowling pins beneath an upwardly movable backstop, and delivering them without lifting and dropping to conveying mechanism of a pin distributing system for return to the pin spotter, which effects a more rapid delivery of pins to the pin spotter and a speeding up of the game cycle of the machine.

25 It is an additional object of the invention to provide a bowling pin spotting machine having a vertically movable backstop extending transversely across the pit of a bowling alley which can be raised in order to allow fallen pins and bowling balls to be conveyed longitudinally and rearwardly in the pit of the alley beneath the raised backstop onto a ball lift and pin distributing mechanism for return to the player and pin setting mechanism, respectively, after which the backstop is returned to its normal operating position.

30 With these and other objects not specifically mentioned in view, the invention consists in certain combinations and constructions which will be hereinafter fully described, and then set forth in the claims hereunto appended.

In the accompanying drawings which illustrate a preferred embodiment of the invention and form a part of this specification, and in which like characters of reference indicate the same or like parts:

Figure 1 is a side elevation, partly in section, illustrating the rear end of a bowling alley and showing the mechanism constituting the invention arranged in operative relationship thereto;

Figure 1a is a view showing the arrangement of two closely positioned bowling pin spotting machines mounted on a common kickback, and the means for providing sufficient room for a ball to pass between the machines and roll without obstruction along a common ball return runway mounted on a single kickback;

Figure 2 is an end view, taken on line 2—2 of Figure 1 with parts omitted and broken away to illustrate the invention; and

Figure 3 is a plan view with parts omitted showing the arrangement of the ball and pin removing mechanism constituting the invention.

With reference to the drawings, there is shown a bowling alley, indicated generally A, provided with the customary pit P located at the end of the pin supporting bed portion, and kickbacks S located at opposite sides of the pit. At the rear end of the pit is mounted a resilient cushion or backstop C which is employed primarily for the purpose of absorbing the impact of balls rolling into pit P. A ball striking backstop C falls into the pit and its movement is stopped.

The preferred form of backstop is similar in construction to that disclosed in co-pending Hagquist application, Serial No. 654,591, filed March 15, 1946, for Bowling Pin Setting Machine. Backstop C is vertically movable from the position shown in Figure 1, after each ball of a frame is rolled in order that the ball and pins may be conveyed therebeneath to the ball separating and lifting, and pin distributing conveying mechanisms, respectively.

Following the delivery of balls and pins therebeneath, the backstop is lowered into the position shown in Figure 1, preparatory to the rolling of the next ball of the frame. The mechanism for mounting and operating backstop C is described hereinafter.

Pit P is provided with pin and ball receiving, assembling and conveying mechanism which effects the movement of balls and pins received in the pit beneath backstop C, as mentioned hereinabove. In the preferred embodiment illustrated in this application there is provided a suitable conveyor mechanism which moves balls and pins rearwardly in the pit to ball lift L and pin distributing conveyor E, respectively. As shown in Figures 1, 2 and 3, an endless conveyor 14 provided with transverse flights 15 is employed for this purpose. Conveyor 14 may be driven either continuously or intermittently. Conveyor 14 runs upon a roller 16 mounted on shaft 18. Attached to shaft 18 is a sprocket 20 on which runs a chain 22 driven by a sprocket 24 mounted on the shaft of a gear reduction motor 26. The opposite end of conveyor 14 runs upon an idler roller 28 secured to shaft 30. Shafts 18 and 30 are supported in bearing brackets 32, 34, respectively, suitably mounted in pit P. Driven roller 16 is preferably located closely adjacent pin delivery position relative to conveyor E so that the upper lap of conveyor 14 can readily convey the ball and pins out of the pit P beneath elevated backstop C for delivery of a ball onto lift L, and pins into pin distributing conveyor E. The upper lap of con-

veyor 14 extending between rollers 16 and 28 preferably is supported by a plate 36 secured by brackets 38 to an upright rib 40 suitably mounted in pit P.

While conveyor 14 may be of a width extending completely across the width of pit P in order that all pins and balls falling into the pit can be carried by the upper lap to ball lift L and pin distributing conveyor system E, it is preferred that the width be less than the maximum width of the pit in order that a more positive control can be exerted on the pins in order to insure their proper delivery onto conveyor system E. This is because, as indicated in Figure 2, it would be relatively difficult otherwise to feed pins onto the substantially horizontal portion H of conveyor E for upward movement to the pin distributing and spotting mechanism. For this reason there is provided an auxiliary pit conveyor which delivers pins and a ball onto conveyor 14. In the illustrated embodiment this conveyor is a pivoted upwardly movable plate or platform 12 attached to a hinge 42, one part of which is secured to upright rib 40. This arrangement enables platform 12 to be raised and lowered about the hinge at the proper time during the operation of the machine. When platform 12 is raised after the arrival of a ball and pins in the pit, it is evident that any pins and the ball located on platform 12 will be ejected therefrom onto the upper lap of conveyor 14 for removal from pit P.

Secured to platform 12 and preferably therebeneath and adjacent backstop C is a bracket 44 which carries a protruding stud 46 arranged to engage within a slot 48 of a bracket 50 secured to the bottom portion of backstop C.

As mentioned hereinabove, backstop C is mounted for movement into and out of the pit at proper times in order that a ball, or a ball and fallen pins may be conveyed therebeneath into their respective handling mechanisms for delivery to the player and pin supporting mechanism, respectively. The amount of upward movement of backstop C is never less than the maximum diameter of a ball in order that the latter may pass therebeneath without being obstructed.

It is to be noted that in most bowling alley installations, the depth of pit, or the distance from the surface of an alley to the bottom of the pit, is limited to about fourteen inches. American Bowling Congress rules require a minimum distance of nine and one-half inches from the surface of the alley to the pit mat. Hence, unless the pit is made deeper, which is practically an impossibility in most existing structures because of beam structure of the floor and other like factors, it would be impossible for a ball and/or pins to move beneath the cushion or backstop of most existing alleys without major alterations and rebuilding. This problem has been solved by the present invention.

As shown in Figure 1, backstop C in its normal operative position is located with its lower edge closely adjacent the pin receiving platform 12 and the upper lap of conveyor 14. In this way the movement of the ball and pins beneath the backstop is controlled until at the proper time backstop C is raised and the ball and pins may pass therebeneath.

As shown in Figures 1, 2 and 3, the preferred means for movably mounting backstop C consists of two spaced pivotally supported frames designated generally 52 each having a pair of

guide rails 54 in which backstop C is slidably supported. Frames 52 are pivotally mounted on studs 56 each of which is secured in a bracket 58 mounted on the top of one of the kickbacks S. A cable 60 fastened to the top of backstop C adjacent each end is guided over an idler pulley 62. The loose end of each cable is secured to a pulley 64 mounted on shaft 66 (Figure 1) journaled in suitable bearings fastened to the upper portion of the machine frame 68. Shaft 66 is oscillated by means of a pinion 70 fixed thereto which in turn is actuated by a rack 72 (Figure 1) secured to a rod 73 pivotally connected to a lever 74 carrying a cam follower 76 running in a suitable cam track (not shown) in cam 78 mounted on the main cam shaft 80 of the machine. Cam lever 74 is loosely mounted on shaft 82 supported in suitable brackets in frame 68. Rack 72 is maintained in engagement with pinion 70 by means of flanged roller 84 supported by a bracket 86 loosely mounted on shaft 66.

From the above it follows that whenever cam shaft 80 is set into rotation during the operation of the machine, pulley 64 is operated to raise backstop C in frames 52 upwardly and clear of the path of travel of a ball and any pins therebeneath in order that a ball may be properly located on lift L which is then lifted to separate the ball from any pins which have not already been advanced by flights 15 on conveyor 14 onto conveyor E. Cam 78 is provided with a suitable dwell to allow this operation to take place, and during the continued rotation of shaft 80, at the proper time, backstop C is lowered into the position shown in Figure 1 awaiting the rolling of the next ball of the game.

Cam shaft 80 has secured thereto a gear 88 which engages with and is driven by a gear 90 loosely mounted on a sleeve 92 (Figure 2). This sleeve is preferably an integral part of a sprocket 94 secured to a continuously driven shaft 96. Sprocket 94 is driven by a chain 98 running on a sprocket (not shown) on the main drive shaft of the machine (not shown). The hub of gear 90 is provided with a conventional one-revolution clutch 100 of the well known Bliss type or equivalent, the operating member 102 (Figure 1) of which is adapted to engage an actuating lug 104 of a lever 106 pivotally connected to armature 108 of a solenoid 110. This solenoid is connected to an electric control box 112 which contains the electric control mechanism of the machine. The control mechanism is similar in construction and operation to that disclosed in the above mentioned co-pending Broekhuysen application. Since this specific mechanism forms no part of the present invention, further disclosure and showing thereof is omitted in the interest of brevity.

As a bowling ball is thrown down the alley, it breaks a beam of light issuing from a suitable light source coating with a photoclectric cell 114 in a circuit which controls the operation of solenoid 110. As shown in Figure 1, wires 116, 118 constituting a part of the circuit in which photoclectric cell 114 is connected, extend into control box 112 suitably attached to the frame of the machine. When the beam of light is broken, by means of suitable conventional operating mechanism, an electric contact (not shown) located in control box 112 is closed and solenoid 110 is energized pulling in armature 108 which in turn removes lug 104 from contact with and out of the path of actuating member 102 resulting in throwing in clutch 100 and the coupling of driv-

ing sprocket 94 to gear 90 which in turn drives gear 88.

In order to insure that backstop C shall at all times assume a substantially vertical position 5 similar to that indicated in Figure 1, frames 52 are urged forwardly by springs 120 (see Figure 3). Springs 120 preferably are mounted in recesses 121 formed in kickbacks S. The forward end of each of the springs bears against a depending angle piece 122 secured to the bottom end of one of the frames 52; the rear ends of the springs bear against the rear portions 123 of the recesses in kickbacks S.

In the preferred embodiment illustrated in the drawings, the ball and pins in pit P are moved rearwardly beneath the raised backstop C in a generally horizontal plane. Since it is highly desirable that the ball be properly positioned for removal from the pit of the alley and that all pins be separated therefrom for delivery into the pin distributing conveyor E, the ball lift or cradle L (see Figure 1) is located in a generally horizontal plane and is substantially co-planar with the top lap of conveyor 14 which moves the ball and pins rearwardly out of pit P. Due to this arrangement, the ball is always positively delivered upon and located between cross-bars 130 of ball lift cradle L. If any pins are in front of a ball, as it moves onto bars 130, such pins will slide over rods or bars 130 in their movement to conveyor E. If any pins tend to lodge on bars 130 they will drop therefrom onto conveyor 14 as ball lift L is raised and be fed thereby onto conveyor E.

Ball lift L consists of two end brackets 124 (Figure 3) carrying cam followers 126 (Figure 1) running in substantially vertically positioned side guides 128. Brackets 124 are held together by two cross rods 130 spaced apart a distance less than the maximum diameter of a ball and greater than the maximum diameter of a pin, so that the ball will be supported by cradle L, yet pins will drop downwardly between rods 130 as mentioned hereinabove. Brackets 124 are also supported by slide shoes 132 which run in side guides 128 mounted in recessed portions of kickbacks S. Guides 128 extend upwardly above the top edges of kickbacks S and are secured to frame members 134 by means of suitable strips 137. Cables 136 employed for the purpose of raising and lowering ball cradle L are fastened to the top of each of slide shoes 132. Each of the cables 136 is guided over an idler pulley 138 and the free end thereof is secured to a pulley 140. Pulleys 140 are mounted adjacent the ends of shaft 142 journaled in suitable bearings secured to the upper portion of frame 68. Shaft 142 is oscillated at the proper time by means of a pinion 144 which meshes with an actuating rack 146 attached to rod 147 pivotally connected to cam lever 148 loosely mounted on shaft 82. A cam follower 150 on lever 148 engages with a suitable cam track (not shown) in cam 78 mounted on main cam shaft 80. Rack 146 is maintained in meshing engagement with pinion 144 by means of a flanged roller 152 loosely supported in bracket 154 loosely mounted on shaft 142.

Since it is possible that when several pins and a ball are being moved by conveyor 14 and flights 15 thereof rearwardly beneath elevated backstop C, the ball might be moved off cradle L, a stop 178 is mounted above and adjacent the point where conveyor 14 discharges pins into the path of travel of flights 168 of conveyor E. Stop 178 is normally so positioned with respect to the upper lap of conveyor 14 that any pins being moved

towards conveyor E can travel therebeneath into the range of action of flights 168 of conveyor E. Stop 178 is also so located with respect to rods 130 and cradle L that a ball must come to rest in proper position between rods 130 preparatory to being lifted out of the pit of the machine. This arrangement insures that pins positioned in front of the ball will be moved by flights 15 of conveyor 14 into the range of action of the flights 168 for elevation to pin distributing position in the machine without the possibility of jams and clogging of the machine.

At the rear of the space occupied by ball cradle L is mounted a transverse plate 156 which extends the width of the machine and is held between two uprights 158 forming a part of the rear frame of the machine. Spaced from plate 156 and rearwardly thereof is a plate 160 of similar shape extending transversely of the width of the machine and also attached to the rear frame of the machine. Plates 156, 160 enclose the pin distributing elevator E which is driven in proper timed relation by a shaft 162 (Figure 3) through a clutch 164 from a suitable source of power (not shown). Conveyor E is similar in construction and operation to that shown in Rundell patent, No. 2,388,707 and the co-pending Broekhuysen application, referred to hereinabove.

Pin elevating conveyor E preferably consists of a pair of spaced endless chains 166 supported on sprockets mounted in suitable brackets (as shown in Figures 2 and 3). A plurality of flights 168 mounted at spaced positions on chains 166 are operative to carry pins in succession from the pin receiving station adjacent the end of conveyor 14 upwardly to a rectifying and aligning mechanism, designated generally M. The latter is provided with an endless conveyor 165, which is driven in proper timed relation from a suitable source of power (not shown). Mechanism M delivers pins to a loading station for delivery to pin setting mechanism (not shown). Since this mechanism forms no specific part of the present invention and may be the same in construction and operation as that shown in the above referred to Rundell and Broekhuysen patents, further description and disclosure thereof is deemed unnecessary.

Plate 156 is provided with an opening 170 (Figures 1 and 2) substantially as wide as conveyor 14. A stop or gate 172 slidably supported in bracket 174 (Figure 3) is normally so positioned as to prevent movement of a ball from cradle L onto conveyor E, although any pins located in front of a ball can be moved through the space beneath ball locating stop 178 onto conveyor E. Fastened to the lower portion of gate 172 are two angle brackets 176 (Figure 1) which support cross rod 178, which locate and center a bowling ball on cradle L between rods 130. Secured to gate 172 and preferably at the top thereof is an angle bracket 180 to the ends of which are fastened cables 182, each of which is guided over an idler pulley 184 (Figure 3) loosely mounted on a stud supported in a bracket 186. One bracket 186 is secured to plate 156; the other is mounted in a suitable recess in one of the kickbacks S. The free-ends of cables 182 are attached to weights 188 (Figure 2) slidably supported in guides 190. One of the guides 190 is secured to plate 156; the other is mounted in a suitable recess in one of the kickbacks S. Gate 172 normally is held down at the position shown in Figure 1 against the opposing force of weights 188 by an arm 192

secured to one of the slide shoes 132 and resting on bracket 180.

7
Bowling balls are delivered by ball lift L forwardly onto transverse guides 194, 196 which preferably are downwardly inclined towards a point of ejection at one side of the machine for delivery of a ball through a suitable opening in the frame of the machine onto a conventional ball return runway R provided for that purpose. As shown in Figures 1 and 2, movement of a ball along guides 194, 196 is expedited by a belt 198 which engages the ball on the guides and propels it therealong out of the machine and onto the ball return runway R.

8
In a large number of alley installations where space is at a premium, a single kickback is used between two alleys. Two closely spaced kickbacks are also sometimes used with these arrangements. It is evident that more alleys can be located in a given space than when specifications normally considered standard requiring two kickbacks for each alley are followed. Very often a common ball return runway is mounted on a single kickback in order to effect the delivery of balls back to the playing heads of the two alleys served thereby. In such cases where two bowling pin setting machines are mounted on side by side alleys and where the side frames of the machines are secured to the common kickback there is insufficient space provided for the use of a common ball return runway which can receive balls ejected from the two machines for delivery therebetween along the runway and back to the playing heads of the alleys. The prescribed width of a kickback according to American Bowling Congress specifications is two and three-fourths inches which means that when two bowling pin setting machines are mounted on a common kickback, the side frames are spaced a distance apart less than the maximum allowed diameter of a standard ten pin bowling ball which is about eight and five-eighths inches.

Therefore, because the machine disclosed is free of guide cables and mechanism for elevating and handling balls and pins in front of backstop C, it is possible to spread apart, or form the side frame members of the two machines adjacent the common runway R with passage forming sections, such as curved portions or suitable recesses which cooperate with the ball return runway R and provide a space greater than the maximum diameter of a bowling ball so that the latter may move therebetween along runway R and be delivered to the playing heads of the two alleys served by the common runway mounted on the common kickback S.

One way of providing a suitable passage for a ball is shown in Figure 1A. Two frame members 195, 195' representing the side frames of two bowling pin setting machines mounted on a single kickback S support a common ball return runway R. Each frame member 195, 195' is provided with a curved portion or recess 197, 197' which forms a generally circular passage 199 of greater diameter than the maximum diameter of any ball which will roll along runway R back to a bowler at the playing heads of the two alleys. While only two side frames 195, 195' have been shown, it is to be understood that all other side frame members forward of frame members 195, 195' are provided with similar recesses which allow the unobstructed movement of balls along runway R and back to the bowlers on the two alleys.

75
In the operation of the machine, after a ball

has arrived at the pit and unwanted pins have been swept from the alley into the pit, backstop C is raised between the kickbacks by means of the mechanism described hereinabove and at the same time platform 12 is raised through the stud 45-slot 48 connections described hereinabove. Backstop C and platform 12 assume substantially the positions shown in dotted lines in Figure 2. This movement of platform 12 causes the bowling ball and any pins which may have rested on platform 12 to slide onto moving conveyor 14 whence they are moved rearwardly beneath raised backstop C and onto cradle L and to conveyor E, respectively, by cross strips or flights 15 on conveyor 14.

As the ball and pins are moved toward opening 170 by conveyor 14 and flights 15 thereof, the bowling ball is arrested and located between cross rods 130 of ball cradle L by cross bar 178.

Any pins which may precede the bowling ball go through that part of port 170 which is beneath gate 172 and fall onto elevator E and are lifted by flights 168 to conveyor M.

After the bowling ball comes to rest, the continued rotation of cam shaft 80 through the linkage described above, raises the ball cradle L with the bowling ball and upon reaching its uppermost position above backstop C, cradle L is tilted by lug 191 attached to guide 128 and the cradle assumes a position as shown in dotted outline in Figure 1. The ball rolls forwardly onto downwardly inclined ball delivery guides 194 and 196 where it is engaged by a continuously moving belt 198 and moved out of the machine and onto return runway R.

When the ball lift L starts to rise, arm 192 moves upward and out of contact with bracket 180. Gate 172 thereupon rises by action of weights 188 until the port 170 is fully opened or until upward movement of gate 172 is arrested by two lugs 200 located in the path of the rising gate and secured to plate 156. Any bowling pins previously held back by the presence of the bowling ball and ball cradle L are now advanced by the moving conveyor 14 and pass through port 170 onto elevator E where they are lifted to conveyor M. In order to properly guide the bowling pins through port 170, a plurality of guide fingers 202 are provided. Continued rotation of main cam shaft 80 returns the ball cradle L and the backstop C to their original positions (as shown in Figure 1) at the end of each operating cycle.

The invention above described may be varied in construction within the scope of the claims, for the particular device, selected to illustrate the invention, is but one of many possible concrete embodiments of the same. It is not, therefore, to be restricted to the precise details of the structure shown and described.

What I claim is:

1. In a bowling pin setting machine associated with an alley having a pit at one end thereof, a backstop located in said pit, mechanism for conveying a ball and pins received in said pit toward said backstop, supports mounting said backstop with its lower edge located above said conveying mechanism a distance less than the diameter of a bowling ball for preventing the movement of a ball therewith, and means for moving said backstop vertically out of the path of travel of said ball and pins, whereby said ball and said pins may be moved unrestrictedly beneath said lifted backstop.

2. In a bowling pin setting machine associated

with an alley having a pit at one end thereof, a backstop located in said pit, mechanism for conveying a ball and pins received in said pit towards said backstop, supports mounting said backstop with its lower edge located above said conveying mechanism a distance less than the diameter of a bowling ball for preventing the movement of a ball therewith, and means responsive to the rolling of a ball and the arrival of said ball in said pit in front of said backstop for moving said backstop vertically in a plane substantially at right angles to the path of movement of a ball along said alley out of the path of travel of said ball and pins, whereby said ball and said pins may be moved unrestrictedly beneath said lifted backstop.

3. In a bowling pin setting machine for use on an alley having a pit at one end thereof, a backstop having a transversely extending, substantially unbroken bottom edge located in said pit, mechanism mounted beneath said bottom edge of said backstop and extending rearwardly thereof for conveying balls and pins received in said pit towards said backstop, means supporting said backstop with said bottom edge normally in a position spaced from said mechanism a distance less than the diameter of a bowling ball thereby preventing the passage of a bowling ball therewith, means for raising said backstop out of said pit and out of the path of movement of said ball and pins therebeneath, ball guide means, a ball lift at the rear of said backstop, means locating said ball lift in ball receiving position when said backstop is located in position to prevent the passage of a ball therewith, means operative in response to the rolling of a ball and its arrival in said pit for actuating said means for raising said backstop out of said pit to a raised position, whereby said mechanism can move said ball beneath said raised backstop to said lift, and means for moving said lift upwardly with a ball to deliver said ball to said guide means for ejection from said machine.

4. In a bowling pin setting machine for use with an alley having a pit at one end thereof, a backstop having an unbroken substantially vertical ball striking surface located in and extending transversely across said pit and preventing movement of balls and pins therewith, means mounting said backstop for reciprocatory substantially vertical movement into and out of said pit, mechanism for conveying balls and pins received in said pit towards said backstop, means operative in response to the rolling of a ball and the arrival thereof in said pit in front of said backstop for moving said backstop upwardly relative to said pit to provide room for the passage of said ball and pins therebeneath, a ball lift located at the rear of said backstop, means for delivering a ball beneath said raised backstop onto said lift, a ball return device mounted above said backstop, means for moving said lift upwardly to a point of discharge and means at said point of discharge engaged by said lift for turning said lift to discharge said ball therefrom into said device.

5. In a bowling pin setting machine for use with an alley having a pit at one end thereof, a backstop located in said pit and normally preventing the movement of bowling balls and pins rearwardly thereof, means operative in response to the rolling of a ball and after a ball has rolled into said pit for raising said backstop out of said pit to allow said ball and fallen pins to pass

therebeneath, a ball lift cradle located at the rear of said backstop, a pin elevating conveyor located at the rear of said backstop, positively actuated mechanism for moving a ball and all fallen pins beneath said raised backstop onto said lift cradle and said conveyor, respectively, and means for moving said lift cradle upwardly in a path adjacent the rear of said backstop, and ball supporting and guiding means located above and in front of said backstop in position to receive a ball discharged from said lift cradle onto said ball supporting and guiding means for ejection from said machine.

6. In a bowling pin setting machine, a backstop support located adjacent the end of a bowling alley, said backstop support comprising spaced guides, a backstop mounted for substantially vertical movement in said guides from a lowered operative position preventing all movement of pins and balls therewith to a raised inoperative position permitting movement of said pins and balls thereunder, pin and ball handling devices located at the rear of said backstop, and means for moving said backstop substantially vertically upwardly in said guides to said raised position in response to the rolling of each ball of a frame and the arrival of the ball in said pit to form a passage for said ball and fallen pins to pass therebeneath into the range of action of said devices.

7. In a bowling pin setting machine, a backstop support located in the pit of a bowling alley adjacent the end of the alley, said backstop support comprising spaced guides, a backstop normally preventing the movement of a bowling ball rearwardly thereof mounted for substantially vertical movement in said guides, said backstop including a frame, a resilient ball impact receiving member mounted in said frame and positioned to be struck by a ball rolled along said alley and into said pit to stop the movement of said ball, a ball lifting device at the rear of said backstop, a pin conveyor at the rear of said backstop, and means for moving said backstop substantially vertically upwardly in said guides to provide space for the ball and pins to pass therebeneath to said device and said conveyor.

8. In a bowling pin setting machine associated with a bowling alley having a pin supporting bed and a pit, a transverse backstop having an unbroken bottom edge mounted in said pit normally preventing the movement of pins and balls therewith and spaced longitudinally from said bed, ball and pin distributing means located in said pit at the rear of said backstop, a device in said pit for conveying pins and bowling balls towards said backstop, and actuating means for raising said backstop, mechanism operative in response to the arrival of a ball on said device in said pit in front of said backstop for operating said actuating means to raise said backstop above said device a distance greater than the diameter of said ball, thereby providing a passage for said ball and pins beneath said backstop, and means for actuating said device to move said ball and pins through said passage to said distributing means.

9. In a bowling pin setting machine for use with a bowling alley having a pin supporting bed and a pit adjacent said bed, a backstop, said backstop having a transversely extending substantially unbroken bottom edge, a conveying device mounted in said pit for conveying a ball and pins received in said pit towards said backstop, means normally positioning said backstop with said bottom edge located above said device a distance less than the diameter of a bowling ball to prevent all

movement of balls therebeneath, means for guiding pins and balls onto said device, means operative in response to the rolling of a ball into said pit in front of said backstop for raising said backstop a distance greater than the diameter of a bowling ball, and means for operating said device to move pins and balls beneath said raised backstop.

10. In a bowling pin setting machine for use with a bowling alley having a pin supporting bed and a pit adjacent said bed, a backstop, said backstop having a transversely extending substantially unbroken bottom edge, means normally locating said backstop in said pit in position to prevent the movement of balls and pins therebeneath, a conveyor in said pit for conveying a ball and pins received in said pit towards said backstop, mechanism for raising and lowering said backstop including means operative in response to a ball rolling into said pit for raising said backstop above said conveyor a distance greater than the diameter of said bowling ball, and means for operating said conveyor when said backstop is raised to move pins and balls beneath said backstop.

11. In a bowling pin setting machine for use with a bowling alley having a pin supporting bed and a pit adjacent said bed, a conveyor in said pit, a backstop, said backstop having a transversely extending substantially unbroken bottom edge, means normally locating said backstop in said pit and with said bottom edge spaced above said conveyor a distance less than the diameter of a ball in position to prevent the movement of a ball therebeneath, mechanism for raising and lowering said backstop including means operative in response to a ball rolling into said pit for raising said backstop above said conveyor a distance greater than the diameter of said bowling ball, and means for operating said conveyor when said backstop is raised to move pins and balls beneath said backstop, and an auxiliary conveyor in said pit positioned to deliver pins and balls into the range of action of said first-named conveyor.

12. In a bowling pin setting machine for use with a bowling alley having a pin supporting bed and a pit adjacent said bed, a backstop having a transversely extending unbroken bottom edge, a conveyor in said pit for conveying a ball and pins in said pit towards said backstop, means normally locating said backstop in said pit with said unbroken bottom edge positioned to prevent the movement of a ball and pins beneath said backstop, a ball lift at the rear of said backstop, a pin distributing conveyor located rearwardly of said lift, mechanism operative in response to the rolling of a ball into said pit for raising said backstop to provide space therebeneath for movement of said ball thereunder, means for operating said first-named conveyor to move pins and the ball beneath said raised backstop, means for delivering the ball onto said lift and said pins to said distributing conveyor, means for raising said lift to separate said ball from said pins and deliver said ball to a point of discharge, a ball return device mounted above and forwardly of said backstop, and means operative at said point of discharge for effecting the discharge of a ball on said lift forwardly onto said device.

13. In a bowling pin setting machine for use with a bowling alley having a pin supporting bed and a pit adjacent the end of said bed, a main conveyor located in said pit with its operative lap extending longitudinally in said pit, an auxiliary conveyor mounted in said pit and having

a pin and ball supporting surface substantially coplanar with said lap of said main conveyor, means mounting said auxiliary conveyor to deliver a ball and pins onto said main conveyor, a vertically movable transversely extending backstop mounted at the rear of said pit, means normally supporting said backstop in said pit above said main conveyor in a position to prevent movement of balls and pins therebeneath, mechanism operative in response to a ball rolling into said pit in front of said backstop for raising said backstop to provide space for the movement of said ball and pins beneath said raised backstop, a pin distributing conveyor located at the rear of said backstop, said main conveyor being constructed and arranged to deliver pins to said distributing conveyor, means responsive to the raising of said backstop for operating said auxiliary conveyor to deliver pins and a ball lying thereon onto said main conveyor, and means for operating said main conveyor to deliver said ball and pins beneath said raised backstop and to said distributing conveyor.

14. In a bowling pin spotting machine associated with a bowling alley having a pit at one end, a backstop support located adjacent said pit end of said alley and spaced from said end of said alley, said backstop support including spaced substantially vertical guides, a backstop mounted in said guides for substantially vertical movement, a pin and ball receiving and conveying surface in said pit extending between said backstop and said end of said alley, means normally locating said backstop in said pit at a ball stopping position adjacent the bottom of said guides and

5 at a distance from said surface preventing all movement of a ball and pins beneath said backstop, mechanism for moving said backstop to an elevated position above said surface to provide room for the movement of a ball and pins therebeneath, supports mounting said surface in position to guide a ball and pins toward said backstop and beneath said backstop when said backstop is located at said elevated position, a stop adjacent the bottom of said guides, resilient means normally urging said backstop support forwardly against said stop and maintaining said support against substantial rearward movement when struck by a ball, and means for actuating said mechanism to move said backstop substantially vertically upwardly in said guides from said ball stopping position to said elevated position to allow said ball and pins in said pit to move from said surface in a substantially horizontal direction beneath said raised backstop.

RUPERT E. RUNDELL.
